AUTOMATIC SHINGLE GUIDE

Filed July 15, 1929

Fig. 1

UNITED STATES PATENT OFFICE

FRANCIS O. DOME, OF LA RUE, OHIO

AUTOMATIC SHINGLE GUIDE

Application filed July 15, 1929. Serial No. 378,389.

This invention relates to an automatic guide adapted to be used in laying shingles. Plans for many of the more attractive modern dwelling houses, and to a great extent, plans for remodeling old houses, specify shingled sides. In order to secure the desired artistic effect of such plans, it is of the utmost importance that the shingles on the sides be laid with the greatest accuracy, so that the lower edges of each row are in perfect alignment, since any irregularity therein becomes most conspicuous.

A chalk line is practically useless where absolute accuracy is desired and an ordinary straight edge requires a great deal of time and care for securing it in proper position for each course.

With the above conditions primarily in mind, it is an object of the present invention to provide a device which may be easily and quickly set in position with reference to a course of shingles already laid and which, when so set, will automatically provide an accurate guide for the next course. With this device, the side of a house for a portion of its length may be shingled all the way to the top while for the rest of its length not more than the first course has been laid, and the final result will be just as satisfactory and will be effected with less trouble than if the full length of each course is laid before the next one is started.

The invention will be more specifically explained in connection with the accompanying drawings, which illustrate one embodiment thereof.

In the drawings:

Figure 1 is a front elevation of the invention in operative position.

Figure 2 is an enlarged sectional view taken on the line 2—2 of Figure 1.

Figure 3 is an edge view of the invention as viewed from the bottom of Figure 1, the retaining arms being folded.

The invention, as illustrated as used in laying the shingles 5 on the sheathing 6. It comprises a body portion 7 which, in the present instance, is in the form of a flat metal plate. A straight edge 8 is secured to the body portion 7 at its upper edge and may be as long

as desired. The body portion also has one or more extensions 9 projecting above the straight edge 8 and in front of the same and providing spaced points to which a rail 10 is secured. The straight edge 8 is thick enough and the rail 10 sufficiently spaced from the surface on which the straight edge rests, to provide a pocket for receiving the butts of the shingles about to be laid.

Secured to the underside of the body portion 7, is a channel member 11, one side flange of which, as indicated at 12, is adapted to be inserted underneath the course of shingles already laid. The channel member 11 may be secured to the body member 7 by means of suitable bolts 13, and slots 14 are provided, whereby the channel member may be adjusted with respect to the body in accordance with the length of the shingles, which is to be exposed to the weather.

These same bolts 13 may also serve to hold the retaining arms 15 which are preferably bowed and formed from spring metal so tensioned that their lower ends will bear against the surface of the next lower course of shingles and exert sufficient pressure to hold the guide firmly in the position in which it is placed. It is also desirable to provide the lower ends of the arms 15 with spurs 16 which will bite into the wood and aid in retaining the guide in its position.

The guide may also be provided with forwardly extending handles 17 which, in the present instance, are secured to the body portion by the same bolts 18 that secure the straight edge thereto.

In the operation of the invention, the side flange 12 of the channel member is inserted underneath the butts of the last course of shingles laid and the guide is then raised until the butts of this course of shingles engages the bottom of the channel member. The straight edge 8 is then exactly parallel with the line on which the last course of shingles has been laid and provides a gage by which the next course may be laid with the utmost accuracy. It will be understood that after the guide has been placed in position, the retaining arms 15 will be swung downwardly so that their ends engage the

surface of the shingles, as shown in Figures 1 and 2, to hold the guide firmly in position. When the guide is to be reset in another position, the arms 15 may be swung inwardly to the position shown in dotted lines in Figure 1. Thus it will be seen that whenever the device is set as indicated, the straight edge 8 will automatically assume the correct position to provide an accurate gage for the next course of shingles and will be firmly held in such position. It is also to be noted that it is not necessary to complete one course for its entire length before the next course is started.

15 While I have shown and described specifically one embodiment of the invention, it is obvious that the size, shape and general arrangement of the various parts thereof may be considerably modified without departing materially from the scope of the invention as claimed.

What I claim is:

1. A shingle guide comprising a body, means associated with the body for engaging underneath the butts of shingles already laid, means for gaging from said first mentioned means the next course of shingles to be laid, and arms shiftable on said body into position to bear against the shingled surface to support the body or into inactive position where they bear against said body.

2. A shingle guide comprising a body, means associated with the body for engaging underneath the butts of shingles already laid, means for gaging from said first mentioned means the next course of shingles to be laid, and arms pivoted to said body on axes perpendicular to the shingled surface, said arms being shiftable about their axes into position where their ends bear against the shingled surface to support the body or to inactive position where their ends bear against said body.

In testimony whereof I have hereunto signed my name to this specification.

FRANCIS O. DOME.
